US00D868665S

(12) **United States Design Patent** (10) **Patent No.:** **US D868,665 S**
(45) **Date of Patent:** **** Dec. 3, 2019**

(54) **CYLINDER SUPPORT SYSTEM**

(71) Applicant: **WORTHINGTON INDUSTRIES, INC.**, Columbus, OH (US)

(72) Inventor: **James B. Rike**, Mooresville, IN (US)

(73) Assignee: **WORTHINGTON INDUSTRIES, INC.**, Columbus, OH (US)

(**) Term: **15 Years**

(21) Appl. No.: **29/678,488**

(22) Filed: **Jan. 29, 2019**

Related U.S. Application Data

(63) Continuation of application No. 29/641,843, filed on Mar. 26, 2018, now Pat. No. Des. 849,662, which is a continuation-in-part of application No. 29/640,271, filed on Mar. 13, 2018, now Pat. No. Des. 840,908, and a continuation-in-part of application No. 29/565,543, filed on May 21, 2016, now Pat. No. Des. 816,010.

(57) **CLAIM**

The ornamental design for a cylinder support system, as shown and described.

DESCRIPTION

FIG. 1 is a perspective view of a cylinder support system showing a new design;

FIG. 2 is a left side view of the cylinder support system illustrated in FIG. 1;

FIG. 3 is a front view of the cylinder support system illustrated in FIG. 1;

FIG. 4 is a right side view of the cylinder support system illustrated in FIG. 1;

FIG. 5 is a rear view of the cylinder support system illustrated in FIG. 1;

FIG. 6 is a top view of the cylinder support system illustrated in FIG. 1; and,

FIG. 7 is a bottom view of the cylinder support system illustrated in FIG. 1

In the drawings, the broken lines depict unclaimed environmental subject matter only and form no part of the claimed design.

The cut away portions in the drawings indicate the appearance of any portion of the article between the cut away lines forms no part of the claimed design.

1 Claim, 7 Drawing Sheets
